UNITED STATES PATENT OFFICE.

GEORG ALEXANDER KRAUSE, OF MUNICH, GERMANY, ASSIGNOR TO THE FIRM
EDUARD GREUTER & CIE, OF BASEL, SWITZERLAND.

PROCESS OF EXSICCATING OR CONCENTRATING SOLUTIONS.

Application filed June 19, 1920. Serial No. 390,304.

(GRANTED UNDER THE PROVISIONS OF THE ACT OF MARCH 3, 1921, 41 STAT. L., 1312.)

To all whom it may concern:

Be it known that I, GEORG ALEXANDER KRAUSE, citizen of Germany, residing at Munich, Bavaria, Germany, have invented 5 certain new and useful Improvements in the Process of Exsiccatiⁿg or Concentrating Solutions (for which I have filed application in Germany January 29, 1917; Italy, June 9, 1920; Holland, June 18, 1920; Great 10 Britain, June 16, 1920; Switzerland, June 8, 1920); and I do hereby declare the following to be a full, clear, and exact description of the invention, such as will enable others skilled in the art to which it appertains to 15 make and use the same.

My invention relates to improvements in the process of exsiccatiⁿg or concentrating solutions and of carrying out chemical reactions and the object of my invention is to 20 provide a new method which offers certain advantages hereinafter more particularly referred to over the methods heretofore in use.

In describing my invention I refer to the 25 drawing herewith which is a diagram indicating a drying or exsiccatiⁿg compartment in vertical section, as hereinafter explained.

A process is already known in which the 30 fluid intended for evaporation is atomized within an evaporating or drying compartment and spread out in the form of a fine mist against which a current of air is conducted, the rapidity and force with which the said mist moves, permitting, however, 35 the said current to pass through and penetrate the former at its edge only. The current of air in this known process is made to travel upward, from the bottom to the top.

In the said process while the main portion 40 of the exsiccatiⁿed powder, the product of the process, settles in the bottom part of the drying compartment, a larger or smaller portion will be lost, being taken along by the movement of the air-current and escaping 45 with the latter.

In accordance with the present invention the air-current will be conducted against the mist referred to in the opposite direction, namely from top to bottom. In this way 50 I attain the advantage that all of the exsiccatiⁿed product travels in one direction only, namely, towards the bottom of the compartment which considerably cheapens and simplifies the collection and precipita-

tion of the powder. Another advantage of 55 my invention resides in the circumstance that the powder already dried comes into contact only with air the temperature of which has been reduced in the rapidly rotating mist while when the current of air is 60 conducted from the bottom to the top, the main portion of the dry powder is bound to pass in dropping the hot air before the latter has come into contact with the mist. Accordingly, in case of equal sensitiveness of 65 the dry powder against the action of temperatures, higher temperatures of the air may be used in my present invention.

The drawing shows a steam-turbine wheel T in the middle of the compartment 70 and causing the rapid revolution required for the atomization of the solution on a disk or plate S upon which it is being fed through the pipe F. The air is admitted at the top at i entering in currents K which, 75 owing to the force of the rapidly traveling mist N, are unable to enter and penetrate the latter to any extent but are forced to turn aside, being able to penetrate the said mist only at its extreme edges. Finally the 80 air escapes through the outlet A near the bottom of the compartment.

This conduction of the air from top to bottom may be also resorted to in those cases where the mist spreads in a cylindrical or 85 conical shape.

I would mention that in the methods of exsiccatiⁿation connected with the atomization of liquid it is already known to conduct the exsiccatiⁿing agent, that is the air-current 90 referred to, through the drying compartment in downward direction either in counter-current or in a current setting-in in the same direction with the atomized liquid intended for exsiccatiⁿation. But in these 95 heretofore known processes the drying process goes on within the whole drying compartment, with the result that the best possible equal distribution of both the liquid and the exsiccatiⁿing air takes place within 100 the whole compartment. Consequently it is unavoidable with these processes that the drying air in uncooled or partially uncooled condition comes into contact with already exsiccatiⁿed particles. In contradis- 105 tinction with this the present invention solves the problem by the method hereinabove described which consists in that the

drying process is chiefly completed within the disk-shaped mist spreading from the middle of the drying compartment, that the exsiccated solid substance comes into contact only with air of reduced temperature and that in this way with equal sensitiveness of the dry substance against the action of temperature the employment of higher temperatures of the air becomes practicable.

10 I claim:—

The herein described method of desiccating liquid or semi-liquid substances, which consists in feeding the substance to be treated in unatomized condition into a closed chamber, atomizing the substance by

spreading it out horizontally into the form of a relatively thin disc in said chamber, introducing a current of a gaseous drying medium into said chamber in a plane above and substantially parallel with the disc of the substance being treated, and exhausting said current out of the chamber in a plane below said disc.

20 In testimony whereof I hereunto affix my signature in the presence of two witnesses.

GEORG ALEXANDER KRAUSE.

Witnesses:

PAUL DREY,

ANNA NIEDERMAIER.
